(57) **CLAIM**

The ornamental design for an antenna radome, as shown and described.

DESCRIPTION

FIG. 1 is a perspective view of the antenna radome.

FIG. 2 is a front elevational view thereof.

FIG. 3 is a rear elevational view thereof.

FIG. 4 is a left side elevational view thereof, the right side elevation view being a mirror image of the left side elevation view; and,

FIG. 5 is a top plan view thereof.

The bottom view forms no part of the claimed design. The broken lines showing portions of the article form no part of the claimed design.
